TOP UNIT FOR VENDING MOTOR VEHICLES

Thomas Carvel, Chauncey, N.Y.

Application April 10, 1958, Serial No. 50,423

Term of patent 14 years

(Cl. D14—27)

FIG. 1

FIG. 2

FIG. 3

FIG. 4

Fig. 1 is a plan view of a top unit for vending motor vehicles, showing my new design;

Fig. 2 is a side elevation thereof;

Fig. 3 is a front elevation thereof; and

Fig. 4 is a rear view thereof.

I claim:

The ornamental design for a top unit for vending motor vehicles, substantially as shown.
